UNITED STATES PATENT OFFICE

2,669,254

VELOCITY-REDUCING AND FILTERING
INLET FOR HYDRAULIC TANKSGeorge W. Mork, South Milwaukee, Wis., assignor
to Bucyrus-Erie Company, South Milwaukee,
Wis., a corporation of Delaware

Application April 21, 1948, Serial No. 22,445

3 Claims. (Cl. 137—548)

1

My invention relates to new and useful improvements in hydraulic units for the control of tractor equipment more particularly to means for retarding, uniformly distributing, and purifying the liquid in such units to increase operating efficiency.

Such hydraulic units comprise an hydraulic storage tank or tanks, an hydraulic pump, the control valve for controlling the flow to and from the pump, means for actuating the valve, and various incidental conduits, relief valves, and one-way valves. An hydraulic unit of the general sort to which my invention is applicable is described in the copending application of myself and Gottfried Reuter, Serial No. 642,924, filed January 23, 1946, now Patent No. 2,581,340 of January 8, 1952, for Hydraulic Unit, to which application reference is made.

In such hydraulic units, when the circulating liquid is returned to the tank and mixes with the liquid already in the tank, it sets up a turbulence which aerates the liquid. Such aeration is harmful since it causes jerky operation of the cylinder-piston assemblies that actuate the tractor equipment, causes knocking in the conduits, and increases the volume of the liquid which then overflows.

Accordingly the principal object of my invention is to provide a simple, compact, and automatically-functioning means for eliminating such objectionable turbulence in the hydraulic unit.

A further object of my invention is to provide means for effecting uniform distribution of the liquid as it enters the hydraulic unit.

A further object of my invention is to provide means for cleaning the liquid as it passes into the tank.

In addition to the objects above stated, I have worked out a number of novel and useful details, which will be readily evident as the description progresses.

My invention consists in the novel parts, and in the combination and arrangement thereof, which are defined in the appended claims, and of which one embodiment is exemplified in the accompanying drawings, which are hereinafter particularly described and explained.

Throughout the description, the same reference number is applied to the same member or to similar members.

Referring now to the accompanying drawings, it will be seen that:

Figure 1 is a general vertical front elevation of the hydraulic unit to which my invention is applied, the tanks and flow retarder therein being shown cut away in section.

2

Figure 2 is a plan view of my flow retarder, taken along the lines 2—2 of Figures 1 and 3.

Figure 3 is an enlarged vertical section of my flow retarder, taken along the line 3—3 of Figure 2.

Referring now to Figure 1, we see that the hydraulic unit comprises two tanks 11 attached to the sides of main housing 12 which contains most of the conduits and supports the auxiliary pump housing 13, and a control-valve casing 14 resting on top of the main housing. The pump is driven directly by the front power-take-off shaft of the tractor (not shown).

Liquid is normally returned from the valve to each tank through a passage 15 which is located along the side of main housing 12 and leads to opening 16 in tank bottom 17 which is normally completely closed except at opening 16.

Located within the tank are one or more horizontally spaced cylindrical baffles which are preferably vertical and coaxial with opening 16. Each baffle consists of either a lower baffle 18 mounted on and extending upwardly from the preferably flat bottom 17 of the tank, or an upper baffle 19 mounted on and depending from the underside of baffle plate 20 which is supported on and some distance above tank bottom 17 by upstanding bolts 21. The top edge of each lower baffle 18 is spaced below baffle plate 20, and the bottom edge of each upper baffle 19 is spaced above tank bottom 17, so that the liquid passes outwardly successively upwardly and downwardly through the series of compartments 22a—b—c formed by the overlapping portions of the successive lower and upper baffles. The baffles are of progressively increasing diameter, so that the compartments have preferably a constant height, but progressively increasing horizontal cross-section proportional to the square of their radius. As the liquid flows outwardly from one compartment to the next, two effects occur: (1) velocity of the liquid decreases in inverse proportion as the cross section of the compartments increases; and (2) pressure within each compartment is equalized insuring uniform distribution of flow around the periphery of the velocity retarder inlet. This last-mentioned pressure equalization is effected by the baffles which set up a slight back pressure (due to friction and deflection) which equalizes any difference in pressure and resulting non-uniform flow around the inlet due to baffle plate 20 not being exactly parallel to tank bottom 17, or to non-uniform flow at inlet 6.

Thus we see that baffle plate 20 and tank bottom 17 form in effect a Venturi orifice in which there is the velocity retardation normally

characteristic of such an orifice, plus pressure equalization resulting in uniform flow distribution around the outer periphery of the orifice, the latter being accomplished by a series of intermeshing corrugations (or baffles) on the inner sides of the orifice. In the particular preferred embodiment shown in Figures 1-3, the sides of the orifice are in effect two vertically spaced horizontal circular plates, the progressive retardation of velocity being secured by having the liquid move radially outwardly between the plates from their center to their periphery and past a series of intermeshing concentrically circular corrugations located between the plates. In this way turbulence of the liquid emitted by the inlet is eliminated and uniform flow distribution effected by a very compact structure in a space that could not possibly accommodate a conventional trumpet-shaped Venturi orifice.

I prefer to show baffles 18 and 19 in the form of vertical concentric cylinders, instead of outwardly flaring frusto-cones, because, although the latter arrangement would secure more uniform Venturi retardation, my preferred arrangement is simpler to manufacture, especially when the upper and lower walls and their respective plates are cast in one piece. However, it is obvious that such a preferred embodiment shown in the drawings is not essential, and that my invention may be embodied in various other forms.

Turning now to the second feature of my invention, we see that it is possible to utilize my flow retarder also to filter the liquid conveniently by modifying my inlet in two respects. First, I make the outermost upper baffle in the form of a screen. Secondly, I add a trough-shaped screening element 23 around the lower edge of that baffle and extending inwardly across the lower part of the outermost compartment 22c. As liquid is deflected downwardly by the outermost or peripheral of upper baffles 19, any steel filings or other particles of dirt that are heavier than the liquid are thrown outwardly by centrifugal force, some against the baffle and some into the outermost portion of the compartment and so are caught by filter element 23.

Having now described and illustrated one form of my invention, I wish it to be understood that my invention is not to be limited to the specific form or arrangement of parts herein described and shown.

I claim:

1. A velocity-reducing hydraulic-fluid inlet, designed to be submerged in the tank of an hydraulic power system, comprising: two spaced substantially parallel plates; an upstream open-

ing through substantially the center of one of these plates; a series of intermeshing annular baffles, each surrounding the upstream opening, and each projecting substantially perpendicularly from one of said plates; and a peripheral downstream opening, substantially surrounding the upstream opening; said downstream opening being located in the plate-and-baffle assembly adjacent the periphery of the outermost annular baffle; the cross-sectional area of the downstream opening being materially greater than that of the upstream opening; said velocity-reducing hydraulic-fluid inlet being further characterized by the fact that one of said annular baffles is spaced from the opposite plate and from any adjacent baffle so as to leave a space for the passage of liquid therebetween, and by having perforated basket means that is connected to said one of the baffles adjacent the free edge of such baffle and that extends only partly across said space, said basket means thereby catching and holding particles filtered out of the liquid, as the liquid passes through said space.

2. A velocity-reducing hydraulic-fluid inlet, according to claim 1, further characterized by the fact that said one of the baffles is the outermost baffle, and that the basket means is hook-shaped in cross-section and points inwardly upstream.

3. A velocity-reducing hydraulic-fluid inlet, according to claim 2, further characterized by the fact that said outermost baffle itself consists at least in part of a filter screen.
